UNITED STATES PATENT OFFICE.

EDWARD C. MOORE, OF YONKERS, ASSIGNOR TO TIFFANY & COMPANY, OF NEW YORK, N. Y.

DESIGN FOR A SPOON, FORK, OR OTHER TABLE UTENSIL.

SPECIFICATION forming part of Design No. 19,211, dated July 16, 1889.

Application filed May 24, 1889. Serial No. 312,006. Term of patent 14 years.

To all whom it may concern:

Be it known that I, EDWARD C. MOORE, a citizen of the United States, and a resident of Yonkers, Westchester county, New York, have 5 invented a new and original Design for Spoons, Forks, or other Table Utensils, of which the following is a specification, reference being had to the accompanying drawings, which form a part of the same.

10 This invention relates to a design to be imparted to or worked upon spoons, forks, and other table utensils; and it consists in the novel configuration and ornamentation herein specifically shown and claimed.

15 Figure 1 of the accompanying drawings is a front view of a spoon with my design applied thereto, and Fig. 2 is a rear view of the same.

My design is mainly worked upon and imparted to the handle of the table utensil, although a portion of the design extends over 20 the body of the article. The outline of the edges of the handle is composed of a gently-undulating curved line broken occasionally to emphasize a change in the design, and the 25 front and back faces of the handle are ornamented with figures in relief.

My design is composed of two parts—the front A (shown in Fig. 1) and the back B. (Shown in Fig. 2.) The front part A is traversed 30 along each side by a stem-work undulating in outline and having conventionalized leaf ornaments arranged at intervals upon it, the lower end of each stem-work terminating in a scroll. Just below the wider portion of the handle a branch extends from one of the side stems over the other side stem and back again 35 over the first stem in curvilinear lines and scroll form, and curved-leaf and scroll orna-

ments extend from this curved branch. Above these ornaments in the wider portion of the 40 handle the stem-work widens and the leaf ornaments are larger and closer together, and at the upper end of the handle the side stems converge and their ornaments unite.

The back part B is traversed along each 45 side by a stem-work undulating in outline and having conventionalized leaf ornaments arranged at intervals upon it. These stems meet near their lower ends and terminate at their lower ends in scrolls, and an ornamentation mainly composed of curved-leaf forms extends outward from the stem-work at the base of the handle. At the upper and wider portion of the handle the branch work widens and the leaf ornaments are larger and closer 50 together, and the side stems meet at the upper end of the handle.

The characteristic features of this design 55 comprise the undulating stem-work and leaf forms and the leaf and scroll ornaments.

What I claim, and desire to secure by Letters Patent, is—

1. The design for spoons, forks, or other table utensils, consisting of the front A, substantially as shown.
2. The design for spoons, forks, or other table utensils, consisting of the back B, substantially as shown.
3. The design for spoons, forks, or other table utensils, consisting of the front A and 70 the back B, substantially as shown.

E. C. MOORE.
